(57) **CLAIM**

We claim the ornamental design for a nestable shallow container, as shown and described.

DESCRIPTION

FIG. 1 is a bottom perspective view of the claimed design; FIG. 2 is top perspective view of the claimed design of FIG. 1;

FIG. 3 is a top view of the claimed design of FIG. 1.

FIG. 4 is a bottom view of the claimed design of FIG. 1; and, FIG. 5 is a side view of the claimed design of FIG. 1.

The ornamental design which is claimed is shown in solid lines in the drawings. The broken lines in the drawings are for illustrative purposes only and form no part of the claimed design.
